CLAIM

The ornamental design for a garden tool, as shown.

DESCRIPTION

FIG. 1 is a perspective view seen from the front and left
sides of a garden tool showing my new design;

FIG. 2 is a front elevational view thereof;

FIG. 3 is a rear elevational view thereof;

FIG. 4 is a top plan view thereof;

FIG. 5 is a left side elevational view thereof;

FIG. 6 is a right side elevational view thereof; and

FIG. 7 is a bottom plan view thereof.
